UNITED STATES PATENT OFFICE.

HOWARD E. VAN ORDEN, OF EAST ORANGE, NEW JERSEY.

LOCK MECHANISM.

1,278,527.

Specification of Letters Patent. Patented Sept. 10, 1918.

Application filed January 25, 1917. Serial No. 144,334.

To all whom it may concern:

Be it known that I, HOWARD E. VAN ORDEN, a citizen of the United States, and residing at East Orange, in the county of 5 Essex and State of New Jersey, have invented certain new and useful Improvements in Lock Mechanisms, of which the following is a specification, such as will enable those skilled in the art to which it 10 appertains to make and use the same.

This invention relates to lock mechanisms and particularly to devices of this class commonly known as three-point locks, and the object of this invention is to provide an improved device of this class which is simple in construction and operation and adapted for use in connection with doors of any kind or class and of any construction.

The invention is fully disclosed in the following specification, of which the accompanying drawing forms a part, in which the separate parts of my improvement are designated by suitable reference characters in each of the views, and in which:—

25 Figure 1 is an inside view of a part of a door frame and indicating my improvement applied thereto;

Fig. 2 a partial section on the line 2—2 of Fig. 1;

30 Fig. 3 a partial section on the line 3—3 of Fig. 1 on an enlarged scale;

Fig. 4 a partial section on the line 4—4 of Fig. 1 and on an enlarged scale; and,

35 Fig. 5 a partial section on the line 5—5 of Fig. 2, on an enlarged scale and indicating the operation of one of the lock mechanisms.

In the drawing I have indicated at *a* a part of a sheet metal door and at *b* a part of 40 a sheet metal door frame. In the practice of my invention, I provide a lock mechanism of the class described consisting of a plate *c* having a central enlarged portion *c*², and a bar *d* is slidably mounted on said plate 45 and through suitable guide keepers *c*³ secured to the plate *c*, said rod being provided with a central raised portion *d*² and corresponding raised end portions *d*³.

I also provide a plurality of bolts *e*, *e*² 50 and *e*³, the bolt *e*² being pivoted to the central raised portion *d*² of the bar *d* by a screw *f*, while the bolts *e* and *e*³ are pivoted to the raised end portions *d*³ of the rod *d* by screws *f*². The outer end portion of the 55 bolts *e*, *e*² and *e*³ are provided with elongated apertures *e*⁴ through which pass screws

*e*⁵ which are secured to the raised sheet metal plates *g* riveted or otherwise secured to the plate *c*, and said screws *e*⁵ and apertures *e*⁴ form guides for the bolts *e*, 60 *e*² and *e*³.

The outer ends of the bolts *e*, *e*² and *e*³ are adapted to operate in connection with a latch or similar plates *h* secured to the door frame *b* in line therewith, as clearly shown 65 in Figs. 1 and 5 of the drawing.

The bolt *e*² is provided with a supplemental plate *i* having an elongated aperture *i*². Mounted on the screw *f* is a disk or roller *i*³ which is free to rotate thereon and 70 which operates in the elongated aperture in the plate *i*, and mounted on the screw *f* outwardly of the roller *i*³ is a lock plate *j* composed of two cylindrical parts *j*² and *j*³, the part *j*² operating in connection with the 75 screw *f* while the part *j*³ is mounted on a screw or pivot pin *k* secured to a raised plate *m* which is riveted to, or otherwise secured to the enlarged portion *c*² of the plate *c* and which forms a part of a lock casing. 80

The part *j*³ of the lock plate *j* is provided with inwardly directed finger pieces *j*⁴ and an outwardly directed stud *j*⁵ having wings or ears *j*⁶. Mounted in the door *a*, and the enlarged portion *c*² of the plate *c* is a suitable cylinder lock mechanism *n* operated by 85 a key in the usual manner, which is not shown, and connected with the rear end portion of the cylinder of said lock mechanism is a plate *n*² having inwardly directed fingers *n*³ which are adapted to operate in connection with the wings or ears *j*⁶ on the part *j*³ of the lock plate *j*, whereby the insertion 90

of a key into the lock *n* and the rotation of the cylinder of said lock will move the fingers *n*³ to rotate the lock plate *j* which, in turn, swings the part *j*² of said lock plate on the screw or pivot pin *k* from the position shown in full lines in Fig. 5 to that shown in dotted lines in said figure, which operation raises the bar *d* and moves the bolts *e*, *e*² and *e*³ inwardly, or out of engagement 95 with the latch plates *h* in the door frame as clearly indicated in Fig. 5.

The above operation of moving the bolts *e*, *e*² and *e*³ inwardly may also be accomplished from the inner side of the door, by grasping the finger pieces *j*⁴ and rotating the part *j*³ of the lock plate *j* in the same manner as said plate is rotated by the lock 100 mechanism *n*.

The raised plate *m* which forms a part

of the lock casing is provided with arc-shaped apertures m^2 in which the fingers n^3 operate, as clearly indicated in Figs. 1 and 4 of the drawing.

- 5 When the bolts e , e^2 and e^3 are in the position indicated in dotted lines in Fig. 5, the same may be moved outwardly by the rotation of the cylinder of the lock mechanism by a key in the usual manner, or by 10 rotating the lock plate j by hand, or by grasping the finger pieces j^4 , as will be readily understood, and the downward movement of the bar d to bring the bolts e , e^2 and e^3 into their operative position is 15 limited by the guide keeper c^3 below the lock mechanism, as clearly indicated in Fig. 3 by the central raised portion d^2 striking the same.

My invention resides in the bar d or a 20 single element having a plurality of bolts pivotally connected therewith and suitable means for operating the bar to project and withdraw the said bolts to lock or open a door of any kind or class, the invention 25 being not limited to any specific form of lock mechanism for accomplishing this result, and changes in and modifications of the construction herein shown and described may be made, within the scope of the appended claims, without departing from the 30 spirit of my invention.

While I have shown my improvement applied to a sheet metal door and door frame and without an inclosing casing of any kind 35 or class, it will be understood that the entire lock mechanism may be inclosed in a suitable casing, or the central portion of said mechanism inclosed, if desired.

Having fully described my invention, 40 what I claim as new and desire to secure by Letters Patent, is:—

1. A door lock of the class described, comprising a bar movable longitudinally of the door, lock bolts pivoted directly to said bar 45 and movable transversely of the door, a lock mechanism mounted in said door and a lock plate mounted in connection with said bar and in connection with said lock mechanism, said plate being adapted to be operated by 50 said lock mechanism to move said bar longitudinally of the door, and a hand-operated device for operating said lock plate independent of said lock mechanism to move said bar longitudinally of the door.
- 55 2. In a door lock of the class described, a lock bar movable longitudinally of the

door, and means for operating said bar consisting of a pivoted lock plate the free end of which is in operative connection with said bar, a cylinder lock mounted in the door, 60 means connected with the cylinder of said lock adapted to engage the pivoted end of said lock plate to operate the same to move the bar longitudinally of the door, and hand-operated means for operating said lock plate 65 independent of said cylinder lock to move said bar longitudinally of the door.

3. In a door lock of the class described, a bar mounted to move longitudinally of the door, a plurality of bolts pivoted directly 70 to said bar, a cylinder lock mounted in said door, a lock plate pivoted rearwardly of said cylinder lock and adapted to be operated by means connected with said lock, one of said bolts being provided with an enlarged head 75 portion having an elongated aperture and the free end of said lock plate being provided with a part adapted to operate in said aperture in the movement of said lock plate by said cylinder lock to move said bar longitudinally of the door and to move said bolts inwardly and outwardly, and means for guiding said bolts in their movement.

4. In a door lock of the class described, a bar mounted to move longitudinally of the door, a plurality of bolts pivoted directly to 80 said bar, a cylinder lock mounted in said door, a lock plate pivoted rearwardly of said cylinder lock and adapted to be operated by means connected with said lock, one of 85 said bolts being provided with an enlarged head portion having an elongated aperture and the free end of said lock plate being provided with a part adapted to operate in said aperture in the movement of said lock plate by said cylinder lock to move said bar longitudinally of the door and to move said bolts inwardly and outwardly, and means for guiding said bolts in their movement.

In testimony that I claim the foregoing as my invention I have signed my name, in 95 presence of the subscribing witnesses, this 24th day of January, 1917.

HOWARD E. VAN ORDEN.
